C. S. MANCHESTER

HEATER

Filed Sept. 7, 1922

UNITED STATES PATENT OFFICE.

CLIFFORD S. MANCHESTER, OF OCEAN PARK, CALIFORNIA.

HEATER.

Application filed September 7, 1922. Serial No. 586,608.

To all whom it may concern:

Be it known that I, CLIFFORD S. MAN-

CHESTER, a subject of Canada, residing at

5 Ocean Park, in the county of Los Angeles,

State of California, have invented new and

useful Improvements in Heaters, of which

the following is a specification.

My invention relates primarily to a heater

for use in citrus orchards, and the object

10 thereof is to provide a heater which is sim-

ple in construction and which will store and

hold a charge of fuel, which when burned

will burn slowly and will raise the tempera-

15 ture in the immediate vicinity of the heater

sufficiently to prevent serious injury to the

fruit on the tree near which the heater is

set and will retain the temperature above the

normal temperature of the air outside the

influence of the heater for several hours.

20 A further object is to provide a heater which

when required for use in a citrus orchard

can be quickly lighted.

In the drawings forming a part of this

25 application, Fig. 1 is a central vertical sec-

tion of my heater as designed for use in a

citrus orchard, the fuel being omitted. Fig.

2 is a section on the line 2—2 of Fig. 1.

Referring to the drawings my heater con-

sists of a starting pan 5, which is shown as

30 made from cast iron, but can be made of

sheet metal pressed and stamped. The side

walls 6 of the pan are preferably at an an-

35 gle of forty-five degrees to the plane of the

bottom of the pan. In the upper portion of

walls 6 are draft ports 7 which are prefer-

40 ably equally spaced apart, and the sum of

the areas of these ports is preferably equal

to one fifth the area of the top plane of the

outlet.

40 In the bottom of the pan is a shallow

well or depression 8 for the reception of the

starting fluid, not shown. Resting upon the

top of the pan is the fuel grate 9 whose bars

are preferably radial. The grate is pro-

45 vided with an upstanding collar 10 which

at one point slopes outwardly and forms a

spout 11 which receives and guides the

starting fluid into the well in the pan. Se-

50 cured to collar 10 are the vertical walls 12

preferably of sheet metal which form the

combustion chamber 13. The grate, collar

and walls of the combustion chamber are preferably circular. Preferably at four equi-distant points and secured to the top of walls 12 are pockets 14 into which are received the legs 15 of the sheet metal deflector 16 to hold the deflector spaced above walls 12. It will be observed by this construction that I direct the air entering the draft ports toward the center of the combustion chamber, thereby centralizing the flame from the starting fuel when the heater is lighted. This centralization of the flame of the starting fuel insures the ignition of the charge of fuel in the combustion chamber with a less amount of starting fuel than would be required if the flame were not so centralized.

Operation.

70

For ordinary use enough carbon briquettes or lump coal or other fuel is placed upon the grate to burn when lighted for three hours. The deflector would then be positioned and the heaters set, one at each 75 tree to be protected. When the temperature of the orchard reaches what is known as the danger point the operatives take cans of coal oil or gasoline and pour the required quantity into well 8 and light the same. 80 By the time the liquid is burned out of well 8 the fuel in the combustion chamber is lighted and continues to burn until consumed, thereby giving out sufficient heat to prevent serious damage to the fruit on the 85 trees of an orchard equipped with my heaters.

Having described my invention, I claim—

1. A heater comprising a metal pan hav- 90 ing draft ports in the side walls; a grate having radial bars mounted upon the top of said pan; walls forming a combustion chamber mounted upon said grate; and a deflector mounted upon the walls of the combustion chamber and spaced therefrom. 95

2. A heater comprising a metal pan hav- 100 ing draft ports in the side walls, said walls being at an angle of forty-five degrees to the plane of the bottom of the pan; a grate hav- ing radial bars mounted upon the top of said pan; walls forming a combustion chamber mounted upon said grate; and a conical de-

2
flector mounted upon the combustion chamber walls and spaced therefrom.

3. A heater comprising a casing forming a combustion chamber; a grate in the bottom of said casing; and a pan below said grate adapted to hold a starting fuel, said pan having ports adapted to cause the cen-

tralization of the flame from the starting fuel in the central portion of the combustion chamber casing.

In witness that I claim the foregoing I have hereunto subscribed my name this 4th day of August, 1922.

CLIFFORD S. MANCHESTER.
